BODY MOLDING GARMENT

Hallie Lee Jasper, Bridgeport, Conn.

Application February 1, 1941, Serial No. 376,982

2 Claims. (Cl. 2-37)

The present invention relates to an improvement in body molding garments, and has for an object to provide a garment, particularly of the girdle type, which will effectually mold and confine the contours of the body in a hygienic manner and without discomfort. The female human body usually protrudes at the high point of the abdomen at the front and at the high point of the buttocks at the rear, and these high points are at substantially offset vertically spaced levels, so that a line or plane connecting them is at a substantial upward inclination from the rear to the front, and it is an object of the present invention to provide a garment in which the forces and strains are directly co-related to this biased or inclined line or plane.

In girdles heretofore in use the elastic material has been so arranged that the body was simply encircled and confined by closing and contracting the girdle in a substantially horizontal direction, the elastic material being so arranged that its pull on the parts under pressure was not directly co-related in its direction between the high points of the front and rear of the body. As a result the molded and reduced areas were directed through the strains of the flattening and reducing process in unnatural directions, producing objectionable bulges and uncomfortable and injurious pressures on the body. Furthermore, the strains of confining the high points of the body at the front and rear were directed along different and divergent lines, working at cross purposes to each other and upon parts of the body which should be substantially free of pulling strains to allow for the displaceable expansion in such parts of the body produced through the reducing pressures applied to the high points of the abdomen and buttocks. These previous garments have been such, for instance, that the pull from the reduced abdominal region has been directly applied to the waist region at the back, while the pull from the reduced buttocks region has been directly applied to the groin and thigh regions at the front, thus so restraining these regions that displaceable expansion in them was prevented and the garment was rendered uncomfortable and injurious, particularly when assuming bending or sitting postures.

It is proposed in carrying out the objects of the present invention to provide a girdle having a bias stretch and pull at each side between the front and back, operating parallel and in direct line with the inclined line or plane between the high points of the abdomen and the buttocks, so

that in the respective compressing and reduction of each of these regions they will each exert a direct and balanced pulling force on the other, thus relieving the upwardly and downwardly adjacent areas of the body, i. e., the waist, thigh and groin areas, from excessive pulling strains and allowing the free movement and flow of the displaceable expansion in these areas resulting from the reducing pressures applied to the abdomen and buttocks.

It is proposed to provide elastic bands at each side having relatively high elastic strength and being relatively wide to extend substantially above and below the high points of the abdomen and buttocks, and arranged parallel to the inclined line or plane between these high points. It is further proposed to provide elastic band portions above and below the elastic bias band portions of relatively less elastic strength, so that the areas of the body engaged thereby will allow for free displaceable expansion of the body as the high points are compressed, while at the same time molding and confining these areas in a gradual and gentle manner, so that there will be no excessive bulging or discomfort. At the same time the inclined arrangement of these relatively more yielding band portions in parallel relation above and below the pressure applying bias band portions permits the wearer to assume different postures, as bending or sitting, with extreme ease and without causing the garment to ride on the figure.

With the above and other objects in view an embodiment of the invention is shown in the accompanying drawing, and this embodiment will be hereinafter more fully described with reference thereto, and the invention will be finally pointed out in the claims.

In the drawing:

40 Fig. 1 is a front view of a girdle type of garment, according to the illustrated exemplary embodiment of the invention.

Fig. 2 is a rear view thereof, partially in section.

45 Fig. 3 is a sectional view, taken along the line 3-3 of Fig. 1.

Fig. 4 is a side view showing the garment as worn, and showing diagrammatically in dotted lines the outline of the body before having the garment placed thereon.

Similar reference characters indicate corresponding parts throughout the several figures of the drawing.

Referring to the drawing, the invention according to the drawing, the invention according to the exemplary embodiment illustrated

therein, comprises a front panel 10, of non-elastic material and of suitable shape, preferably wide at its center portion, convergingly curved inwardly toward its lower end, and divergingly curved outwardly toward its upper end, and a back panel 11, also formed of non-elastic material, having its side edges cut along slightly convexly curved lines, and provided at its upper edge with a V-shape gusset opening 12.

Each of the side portions 13-13 consists of a piece of woven elastic material having longitudinal stretch, and being preferably non-stretchable transversely, this material having a wide band 13^a intermediate its longitudinal edges having relatively closer weave and substantially greater elastic strength than the band portions 13^b and 13^c above and below it. While the bands 13^a, 13^b and 13^c are preferably integrally woven it will be understood that they may be separately formed and stitched together by elastic or stretchable stitching, and also that the bands 13^b and 13^c may have two-way stretch, while the band 13^a has one-way stretch.

The material of the two side pieces is cut along the front and back edges which are butted and secured along the vertical center lines of the front and back panels 10 and 11, the cutting lines being bias to the length of the bands 13^a, so that in the position of the garment on the wearer the bands 13^a are inclined downwardly from front to rear in parallel relation to the inclined line or plane, indicated by the dot-and-dash line A-B in Fig. 4, between the high points of the abdomen and buttocks, and the upper and lower edges of the bands 13^a are substantially equally spaced above and below said line. The upper edges of the waist engaging band portions 13^b and the lower edges of the thigh and groin engaging band portions 13^c are suitably shaped to fit the figure, these edges usually curving downwardly from front to rear.

The meeting edges of the elastic side portions at the front are secured in butted relation by a stitched tape 14 at the inner side, the front panel 10 being secured at its edges by stitching 15 over the outer surface of the side portions 13 at each side of the tape. The meeting edges of the elastic side portions at the rear are similarly secured by a stitched tape 16, and the rear panel 11 is secured at its edges by stitching 17 at each side of the tape 16, portions of the band portions 13^b being secured in the gusset opening 12 by the stitching 17 extending along the edges of this opening to thus provide an elastic web therein.

At one side extending downwardly from the upper edge in right angular relation to the longitudinal edges of the band portion 13^a there is provided an opening 18, secured by a slide fastener 19, this opening being cut in a slight V-form, so that upon being secured in parallel relation by the slidefastener the upper edge of the garment will be slightly contracted, and will therefore be drawn into snug engagement with the waist of the wearer. In a corresponding position at the other side there is provided a cut 20, also cut in a slight V-form, and secured in parallel butted relation by a stitched binding tape 21 at the outer side and a stitched binding tape 22 at the inner side.

The upper edge of the garment is provided at its inner side with an elastic binding tape 23, secured by zig-zag stretchable stitching 24, and the lower edge is similarly provided at the inner

side with an elastic binding tape 25, secured by zig-zag stretchable stitching 26.

Garters 27 are provided at suitable points along the lower edge.

As shown clearly in Fig. 4 the wide elastic bias bands 13^a extend parallel to the line or plane A-B drawn between the high points of the abdomen and the buttocks, so that as these high points, indicated by the dot-and-dash lines C and D before engagement by the garment, are compressed and reduced the lines of the pulling forces are in opposite directions along the same lines, and consequently there is set up a compensatingly balanced relationship between these parts of the body whereby the compressive strains on one part provide the force or power to exert the force or power to exert compressive strains on the other part, and without producing injurious and excessive strains on other parts of the body. At the same time the relatively more yieldable band portions 13^b and 13^c allow for the displaceable expansion resulting from the reducing compression of the abdomen and buttocks in a gradual and gentle manner and without excessive restraining pressures, so that the molded body lines are free from unsightly bulges and the garment will be entirely comfortable and hygienic under all conditions of use and in different postures of the wearer, as standing, bending, sitting and lying down.

I have illustrated and described a preferred and satisfactory embodiment of the invention, but it will be understood that changes may be made therein, within the spirit and scope thereof, as defined in the appended claims.

Having thus described my invention, what I claim and desire to secure by Letters Patent is:

1. In a body molding garment, a body encircling band, adapted for engagement about the abdomen and the diagonally downwardly offset buttocks of the wearer, comprising a woven one-way stretch elastic band part at each side having longitudinal elasticity, the upper and lower longitudinal edges of each of said band parts being parallel to each other and to the direction of one-way stretch, and the front and rear edges being bias to the longitudinal direction of stretch, the front edge forming an acute angle with the upper edge and the rear edge forming an obtuse angle with the upper edge, said band parts at each side being connected together at their front and rear edges, which front and rear edges are adapted in the use of the garment to directly overlie the abdomen and buttocks and whereby there is a direct diagonal pull parallel to said direction of one-way stretch through said band parts between the high points of the abdomen and buttocks, the upper and lower longitudinally elastic edges of the band, respectively, adapted to exert pull in a diagonal direction upwardly from the rear to the front between the horizontally opposed rear waist portion of the body and the abdomen, and in a diagonal direction downwardly from the front to the rear between the horizontally opposed front groin portion of the body and the buttocks.

2. In a body molding garment, a body encircling band, adapted for engagement about the abdomen, and the diagonally downwardly offset buttocks of the wearer, comprising a woven one-way stretch elastic band part at each side having longitudinal elasticity, each including a one-way stretch medial band portion, the upper and lower longitudinal edges of which are parallel to each other and to the direction of one-

way stretch, and upper and lower marginal band portions parallel to and having stretch parallel to the direction of one-way stretch of said medial band portion, and the front and rear edges of each of said band parts being bias to the longitudinal direction of stretch, the front edge forming an acute angle with the upper edge and the rear edge forming an obtuse angle with the upper edge, said band parts at each side being connected together at their front and rear edges, which front and rear edges are adapted in the use of the garment to directly overlie the abdomen and buttocks and whereby there

is a direct diagonal pull parallel to said direction of one-way stretch through said band parts between the high points of the abdomen and buttocks, the upper and lower longitudinally elastic marginal band portions of the band, respectively, adapted to exert pull in a diagonal direction upwardly from the rear to the front between the horizontally opposed rear waist portion of the body and the abdomen, and in a diagonal direction downwardly from the front to the rear between the horizontally opposed front groin portion of the body and the buttocks.

HALLIE LEE JASPER.
